UNITED STATES PATENT OFFICE.

BYRD A. PAGE, OF PETERSBURG, VIRGINIA.

DESIGN FOR A SPIGOT AND BUNG-BORER.

SPECIFICATION forming part of Design No. 30,195, dated February 14, 1899.

Application filed December 31, 1898. Serial No. 700,861. Term of patent 7 years.

To all whom it may concern:

Be it known that I, BYRD A. PAGE, a citizen of the United States, residing at Petersburg, in the county of Dinwiddie and State of Virginia, have invented and produced a certain new and original Design for a Spigot and Bung-Borer, of which the following is a specification.

My invention relates to a new design for a bung-borer and spigot and is illustrated in the accompanying drawing, wherein the figure is a perspective view.

The leading feature of my design consists in a spigot and bung-borer wherein the spigot has a discharging-mouth and is formed with a hollow tubular screw-threaded extension decreasing in diameter toward the end of the screw-threaded extension, from the upper portion of which projects a semicircular sharp-edged continuation converging to a spirally-threaded point, which is in the same plane therewith.

In the said drawing the reference-numeral

1 indicates the discharging-mouth, 2 the hollow screw-threaded extension, which diminishes in diameter toward the termination of the screw-threaded extension, and 3 the semicircular continuation which projects from the upper portion of the screw-threaded extension and is formed with thin or sharp edges converging into a spirally-threaded point 4, that lies in the same plane therewith.

My design presents a spigot and bung-borer of novel, pleasing, and distinguished appearance.

Having thus described my invention, what I claim is—

The design for a spigot and bung-borer as herein shown and described.

In testimony whereof I have hereunto set my hand in presence of two subscribing witnesses.

BYRD A. PAGE.
